[57] CLAIM

The ornamental design for a seat cushion, as shown and described.

DESCRIPTION

FIG. 1 is a front perspective view of a seat cushion, showing my new design;

FIG. 2 is a rear elevational view looking in the direction of the arrows 2—2 of FIG. 1;

FIG. 3 is a top plan view;

FIG. 4 is a side elevational view looking in the direction of the arrows 4—4 of FIG. 3;

FIG. 5 is a side elevational view looking in the direction of the arrows 5—5 of FIG. 3;

FIG. 6 is a front elevational view;

FIG. 7 is a bottom plan view; and

FIG. 8 is a perspective view of the seat cushion, a chair being shown therein in broken lines for illustrative purposes only.
